BOARD DROP HAMMER

Filed July 15, 1926

INVENTOR

UNITED STATES PATENT OFFICE

HARRY G. KIMBALL, OF BRONXVILLE, NEW YORK, ASSIGNOR TO THE BILLINGS & SPENCER COMPANY, OF HARTFORD, CONNECTICUT, A CORPORATION OF CONNECTICUT

BOARD DROP HAMMER

Application filed July 15, 1926. Serial No. 122,570.

The invention relates to improved means for controlling the roll friction in apparatus of this kind and more particularly in multiple roll-set drop-hammers, that is to say, in which more than one pair of lifting rolls are used for lifting the hammer. Heretofore, various means have been proposed for transmitting the weight of the friction bar equally to the rolls of the several roll-sets so as to cause them to grip the board with equal friction, but on account of the great weight and inertia of the mechanism constituting the pressure-distributing system, as well as of the rolls themselves, exact equalization of pressure acting on the board has been difficult to obtain in the first instance, and still more difficult to maintain under rapid operation. According to the present invention, the pressure-distributing system, as such, is eliminated, and the desired pressure for each set or pair of rolls is obtained by the use of a spring or springs so that it is subject to adjustment and can be made absolutely equal to the pressure exerted by the other roll-sets, or otherwise as desired, and when once adjusted will remain undisturbed by inertia influences, even under the highest speed operation.

The accompanying drawings illustrate the principle of the invention.

Figure 1 shows a front elevation of an ordinary board drop hammer having two pairs of lifting rolls with this invention applied;

Figure 2, a larger scale side elevation of the roll head thereof, with parts in section and broken out;

Figure 3, a plan partly in section of the roll head, and

Figure 4, a front elevation of the roll head with parts in section.

The invention may be applied to the ordinary types of board drop hammers, such as that indicated at Fig. 1, which has a base 1, two uprights 2 between which the hammer 3 is guided, and a head structure in which the several pairs of lifting rolls are mounted. Any number of such pairs may be used, in accordance with the principle of this invention, but only two are shown in the machine taken for illustration.

The front rolls are marked 4 and 5 respectively and their corresponding rear rolls 4^a and 5^a, and each is fixed on a roll shaft 6. The two rear rolls may be journalled as customary in this art, that is to say, in eccentric bushings or bearings 7, mounted directly in the head structure and having rearward arms 8, movement of which adjusts the rear rolls toward and from the hammer board by reason of the eccentricity. These arms, at opposite ends of each rear roll, are rigidly joined by crosspins 9 and the two crosspins are connected together and to an adjustment rod 10, which is arranged to be adjustably fixed at the back of the machine frame in the usual manner, not shown, so that the rear rolls can be simultaneously adjusted as necessary.

The lower front roll 5 is journalled, by its roll shaft in eccentric bushings or bearings 11, at each end similar to the bushings 7, and the arms 12 of these bushings are joined rigidly by cross-pin 13, and this cross-pin 13 is connected directly or indirectly to the friction bar 14, or to such other hammer-controlled mechanism as may be employed to control the reciprocation of the hammer. The eccentric bushings 11 are directly mounted in the head structure and the forward ends of their arms 12 are split to form clamps to hold the cross-pin 13. It will be apparent that the descent of the friction bar will rock the eccentric bushings 11 so as to move the lower roll 5 toward the hammer board and into frictional lifting engagement therewith.

The upper front roll 4 is also journalled in eccentric bushings 15 at each end, but these bushings are themselves journalled in bearing blocks 16, which latter are mounted to move or slide in suitable ways formed in the head frame as indicated in Figure 2, or otherwise so as to be capable of movement transversely to the plane of the hammer board. The detail design of the bearing blocks and their guiding means is of course subject to variation. Each block is normally pressed toward the end of its path or slide-way, nearest the hammer board, by a strong spring 17, which can be adjusted by the screw 18 acting on the spring through a follower plate 18a. The actuating arms 19 of the eccentric bush-

ings 15 are rigidly joined together by a cross-pin 20, clamped in their split ends, and connected by a link 21 with the cross-pin 13 of the lower front roll, or otherwise connected 5 to the friction bar so that when the latter falls, both arms 19 and 12 are thereby rocked downwardly. This movement moves the upper front roll as well as the lower roll toward the hammer board. The innermost position 10 of the bearing blocks 16, in their slideways, is such that the axis of the upper front roll bushings is at the same distance from the board as that of the lower front roll bushings, so that when the friction bar drops both rolls 15 engage the board simultaneously. The pressure which can be exerted by the upper roll upon the board is obviously limited by the adjustment of the springs 17 and on any pressure in excess of the limit so imposed, 20 the bearing blocks 16 yield, compressing the springs. The spring adjustment is made to equal the pressure which the lower roll exerts on the board so that the pressures on both rolls are substantially equalized. The movement 25 of the bearing blocks themselves is so slight that on the lifting of the friction bar the rolls withdraw from the hammer bar simultaneously and positively and thus neither can drag on the board to impair its 30 uniform friction surface. Obviously the yielding roll mounting above described can be designed in various ways and associated with other means than the particular eccentric bushings 15 for moving the roll relatively 35 to the mounting; obviously a weight or weights can be used in place of the springs, and obviously also, the principle described can be applied to both pairs of rolls or to 40 more than two pairs.

It will be understood that the lower end of the friction bar is guided in a knockoff box 22, which is conventionally shown in the drawings and which contains a catch adapted 45 to hold the friction bar in an elevated position when it has been lifted by the hammer. This catch is released by a cam face on the hammer when the latter falls, thereby letting the friction bar fall, which causes the lifting 50 rolls to grip the board and lift the hammer. In its ascent the stud 24 on the hammer engages a lever 25 fastened to the friction bar and raises the latter until it is again sustained by the catch. The lifting of the friction 55 bar withdraws the rolls from the board and the hammer again falls, and so on until the hammer is prevented from falling by the operation of the board clamp 26 controlled by an operator's foot treadle 27, all as usual 60 in these machines.

The two upper rolls are geared together by gears 28 and driven from a belt pulley 29 fixed to the extended end of the rear shaft 6; the two lower rolls are similarly geared 65 together by gears 30 and driven by the belt

pulley 31 on the rear shaft at the opposite side of the machine.

I claim:

1. In a multiple roll-set, board drop-hammer, the combination of one roll of one of the pairs of rolls, a yielding mounting therefor, hammer-controlled means for moving said roll, relatively to said yielding mounting, toward and from the hammer board, and a roll of another pair also moved by said means. 75

2. In a multiple roll-set, board drop-hammer, the combination of one roll of one of the pairs of rolls, a yielding mounting therefor, means for urging the mounting toward the board, hammer-controlled means for moving 80 said roll relatively to said yielding mounting, and a roll of another pair also moved by said means.

3. In a multiple roll-set, board drop-hammer, the combination of one roll of one of the pairs of rolls, a yielding mounting therefor, means urging said mounting inwardly against a fixed inward limit or abutment, hammer-controlled means for moving said roll in both directions relatively to said yielding mounting, and a roll of another pair also moved by said means. 90

4. In a board drop hammer, a plurality of pairs of lifting rolls, a yielding roll mounting for one of the rolls of one of the pairs of rolls, means urging said mounting toward the board, an actuating arm for moving the axis of said roll relatively to said mounting, an actuating arm for one of the rolls of another pair of rolls, a rigid connection between said 100 arms, and hammer controlled mechanism for moving said arms. 95

5. In a board drop hammer, a plurality of pairs of lifting rolls, a yielding roll mounting for one of the rolls of one of the roll sets comprising bearing blocks having ways in which they may yield away from the hammer board, springs normally holding said blocks at the inward limits of their ways, a lifting roll carried by said blocks, another lifting 110 roll and hammer-controlled mechanism for moving the axes of both rolls with reference to the board.

In testimony whereof, I have signed this specification.

HARRY G. KIMBALL.
